UNITED STATES PATENT OFFICE.

ARTHUR WILLIAM HULSON AND JOHN WILLIAM HULSON, OF KEOKUK, IOWA.

LOCOMOTIVE GRATE.

1,413,986.

Specification of Letters Patent. Patented Apr. 25, 1922.

Application filed September 11, 1920. Serial No. 409,672.

To all whom it may concern:

Be it known that we, ARTHUR W. HULSON and JOHN W. HULSON, citizens of the United States, residing at Keokuk, in the county of Lee and State of Iowa, have invented certain new and useful Improvements in Locomotive Grates; and we do declare the following to be a full, clear, and exact description of the invention, such as will enable others skilled in the art to which it appertains to make and use the same.

This invention relates to improvements in furnace grates and more particularly to those intended principally for use on locomotives.

The grates now used on locomotives are provided at either their front or rear end with a section called a dumping grate, this section being dropped below the surface of the grate to dump the fire at the end of a run, but while the engine is on the road this section cannot be moved, with the result that ashes build up thereon and cut off all draft therethrough. It is our object, however, to provide a grate section which may be swung above the grate when cleaning off all fire and ashes at the end of a run, and to equip said section with movable grate bars which may be operated while the engine is on the road, to prevent accumulation of ashes and consequent choking of draft. The ash pans of practically all locomotives are too close to the grates to permit a downwardly swinging grate section to be used to advantage to provide a hole of convenient size at either end of the grate through which the fire may be scraped at the end of a run, and hence we pivotally mount the grate section at one edge and swing it upwardly into the fire box. By so doing a much larger hole may be formed in the grate, through which to rake the fire.

In carrying out the above end, a further object is to provide a construction which will permit grate bars of the usual length to be mounted on the aforesaid upwardly swinging grate section, this being permitted by recessing the ordinary grate supporting bars to receive a pair of arms carrying the grate bars of said section.

Yet another object is to provide ledges for supporting the vertically swinging arms when in lowered position, thereby taking all strain of supporting the fire-bed from the

pivotal mounting of said arms and overcoming any possibility of the weight of the fire having a tendency to dump the grate as might otherwise occur.

With the foregoing and minor objects in view, the invention resides in the novel construction and arrangement of parts herein-after described and claimed, the descriptive matter being supplemented by the accompanying drawings.

Figure 1 is a horizontal sectional view of a portion of a locomotive fire-box, illustrating a top plan view of the improved grate.

Figure 2 is a longitudinal sectional view taken substantially on line 2—2 of Fig. 1.

Figure 3 is a vertical transverse sectional view cut approximately on line 3—3 of Fig. 2.

In the drawings above briefly described, the numeral 1 designates a portion of a locomotive fire-box, said box being provided with a plurality of horizontally spaced grate supporting bars, two of which are designated by the numerals 2 and 3. The bar 2 is located at one side of the fire-box and supports one end of each of the several grate bars forming one longitudinal section of the grate, the other ends of said bars being supported by the bar 3 which will also support one end of each of the grate bars of the next adjacent section. For sake of illustration, only one longitudinal section of the grate is shown, but obviously it may be constructed of any desired number of sections.

A pair of horizontal grate bar supporting arms 4 are disposed at either the front or rear end portions of the bars 2 and 3, adjacent the inner sides of said bars and these bars as shown cut away at 5 to receive the arms 4, whereby the distance between said arms will be the same as that existing between the uninterrupted inner sides of the aforesaid bars, thereby permitting all of the rocking grate bars to be of the same length.

These grate bars are of well known construction and have been designated by the numerals 6 and 6^a, the bars 6 being rockably supported by the longitudinal bars 2 and 3, while the trunnions at the ends of the bars 6^a are rotatably received in appropriate openings in the arms 4. Provision is made for shaking or rocking all of the bars 6 and 6^a whereby the entire grate may be kept clean to produce maximum heating efficiency.

and provision is also made for swinging the arms 4 upwardly to elevate all of the grate bars 6^a, thereby forming a gap in the grate which will permit the fire to be quickly 5 raked therethrough.

The arms 4 are pivotally mounted at their outer ends in all instances and it is preferred that this pivotal mounting be formed by a transverse rock shaft 7 to which the 10 outer ends of said arms are secured, the ends of said shaft 7 being rockably mounted in any preferred manner upon the bars 2 and 3. A guard or grating 8 preferably extends over the rock shaft 7 and is suitably secured to 15 the bars 2-3.

For rocking the shaft 7 to raise the arms 4 as desired, any suitable means can well be employed. However, a depending crank arm 9 is shown on said shaft connected with a 20 link 10 which extends from the lower end of a suitable operating lever 11. When this lever is operated, the link 10 swings the crank arm 9 thereby rocking the shaft 7 and swinging the arms 4 upwardly to elevate 25 the grate bars 6^a as shown in dotted lines in Fig. 2.

For taking the weight of the arms 4 from the rock shaft when said arms are lowered and thereby supporting the weight of the 30 fire independently of said shaft, the inner sides of the supporting bars 2 and 3 are provided with horizontal ledges 12 upon which the arms rest as shown, and at intervals these ledges may be provided with horizontal 35 lugs 13 for direct contact with the arms, as seen for instance in Fig. 3. The ledges in question not only support the weight of the arms 4, the grate bars 6^a, and the fire independently of the rock shaft 7, but said ledges 40 will prevent any possibility of the arms in question swinging downwardly and possibly dumping the fire by accident.

For simultaneously rocking all of the grate bars, said bars are provided with depending 45 crank arms 14 and 14^a the former being carried by the bars 6 whereas the latter depend from the bars 6^a. A horizontal link 15 pivotally connects all of the arms 14 while a similar link 15^a is pivoted to the arms 14^a. 50 Both links 15 and 15^a are pivoted at 16 and 16^a to upstanding ears 17 and 17^a on a main horizontal operating link 18, the pivot 16^a being preferably located directly below the shaft 7 as shown in Fig. 2. The outer end 55 of link 18 is shown connected with the lower end of an operating lever 19 and when this lever is oscillated, reciprocation of all of the links 15, 15^a, and 18 takes place, thereby simultaneously rocking all of the grate bars 6 and 6^a to shake the fire. When the lever 60 11 is operated to swing the arms 4 upwardly for elevating the upwardly swinging grate section, the link 15^a swings on the pivot 16^a, as shown by the dotted lines in Fig. 2.

65 The swinging grate section may be located

at either end of the grate and it will be observed that excessive accumulation of ashes on said section is prevented, due to the fact that its grate bars 6^a are oscillated each time the bars 6 are operated to shake the grate. 70 At the end of a run, the fireman or other attendant shakes the finer portions of the ashes and fire through the grate. A scraper is then used to scrape remaining cinders and the like from the upwardly swinging grate section 75 onto the adjacent part of the grate. This having been done, said swinging grate section is swung upwardly, thus forming an unusually large hole through which all material left in the grate may be scraped. 80

By constructing the device in or approximately in the manner shown and described, it will not only be comparatively simple and inexpensive, but will be highly efficient and desirable, and since probably the best results 85 may be obtained from the details disclosed, such details may be followed. However, within the scope of the invention as claimed, numerous changes in form, proportion and minor details may be resorted to if found expedient. 90

We claim:

1. A grate comprising horizontally spaced supporting members, a pair of horizontal arms adjacent the inner sides of said supporting members and disposed at one end portion of the grate, means pivotally supporting the outer ends of said arms, rocking grate bars mounted on said supporting members and other rocking grate bars mounted on 100 said arms, means for rocking all of said grate bars, means for swinging said arms upwardly to elevate all of the grate bars carried thereby, and means for preventing downward swinging of said arms below the 105 grate. 95

2. A grate comprising horizontally spaced supporting bars, a pair of horizontal arms adjacent the inner sides of said supporting bars and disposed at one end portion of the 110 grate, said inner sides of said bars being cut away to receive said arms and having ledges on which said arms rest, means pivotally mounting the outer ends of said arms, grate bars extending between and mounted on said 115 supporting bars and other grate bars mounted on said arms, means for rocking all of said grate bars, and means for swinging said arms upwardly to elevate all of the grate bars carried thereby. 120

3. A grate comprising horizontally spaced supporting members, a pair of horizontal arms adjacent the inner sides of said members and disposed at one end portion of the 125 grate, means pivotally supporting the outer ends of said arms, means for preventing swinging of said arms below said supporting members, rocking grate bars mounted on said supporting members and other rocking grate bars mounted on said arms, crank 130

arms depending from said grate bars, a horizontal link connecting the crank arms of the arm-carried grate bars, another horizontal link connecting the crank arms of the other 5 grate bars, a main horizontal operating link pivoted to both of the aforesaid links whereby all of the grate bars may be simultaneously rocked, and means for swinging the aforesaid horizontal arms upwardly to elevate all of the grate bars carried thereby.

4. A grate comprising horizontally spaced supporting bars, a pair of horizontal arms adjacent the inner sides of said supporting bars and disposed at one end portion of the 15 grate, said bars being recessed to receive said arms and having ledges upon which they normally rest, a plurality of grate bars mounted on said arms and other grate bars mounted on said supporting bars, means for 20 simultaneously rocking said grate bars, a rock shaft mounted on said supporting bars and rigidly secured to the outer ends of said arms, a crank arm depending from said rock shaft, and means connected with said 25 crank arm for turning said rock shaft to raise the first named arms to elevate the grate bars carried thereby.

5. A locomotive grate having an upwardly swinging frame section and a plurality of 30 fire shaking bars mounted thereon, said frame section having its pivotal axis at one edge of the grate, means for swinging said frame section and fire shaking bars upwardly above the remainder of the grate to 35 form a fire-dumping opening, means for preventing downward swinging of said frame

section below its normal operative position, and means for shaking said bars.

6. A grate comprising horizontally spaced supporting bars, a pair of horizontal arms 40 adjacent the inner side of said supporting bars and disposed at one end portion of the grate, said inner sides of said bars being cut away to receive said arms, means pivotally mounting the outer ends of said arms, 45 means for preventing downward swinging of the arms below said supporting bars, grate bars extending between and mounted on said supporting bars and other grate bars mounted on said arms, means for rocking 50 all of said grate bars, and means for swinging said arms upwardly to elevate all of the grate bars carried thereby.

7. A locomotive grate comprising a main grate section having fire shaking bars, an 55 upwardly swinging frame section at one extremity of said main grate section, the pivotal axis of said frame section being located at one edge of the grate, means for swinging said frame section upwardly to 60 form a fire-dumping opening, means for preventing downward swinging of said frame section below its normal operative position, additional fire shaking bars mounted on said 65 frame section, and common means for simultaneously shaking all of the bars of the grate.

In testimony whereof we have hereunto set our hands.

ARTHUR WILLIAM HULSON.
JOHN WILLIAM HULSON.
